UNITED STATES PATENT OFFICE.

CHARLES WESLEY LEWIS, OF PORTSMOUTH, NEW HAMPSHIRE.

COMPENSATING GRAB PLATE.

Application filed June 14, 1924. Serial No. 720,092.

To all whom it may concern:

Be it known that I, CHARLES W. LEWIS, a citizen of the United States, residing at Portsmouth, in the county of Rockingham 5 and State of New Hampshire, have invented certain new and useful Improvements in Compensating Grab Plates, of which the following is a specification.

This invention appertains to tie handling machines and is an improvement of my Patent No. 1,488,210 issued to me March 26, 1924, and the primary object of the invention is to provide means for permitting the tie handling machine to effectively 10 handle and engage ties of different lengths and more effectively preventing the slipping of the ties during the hoisting and lowering thereof.

A further object of the invention is to provide a novel grab plate carried by the grab arms of the tie-handling machine, the grab plate having slidably connected therewith spring pressed tie engaging cups, the cups being slidably associated with the grab 25 plate, whereby a plurality of ties of different lengths can be conveniently handled.

A further object of the invention is the provision of novelly constructed cups for engaging the ties, whereby slipping movement of the ties is eliminated.

A further object of the invention is the provision of novel means for rigidly connecting the grab arms with the grab plates.

A still further object of the invention is to provide a compensating grab plate for tie handling machines which will be durable and efficient in use, one that will be simple and easy to manufacture, and one which can be incorporated with a tie handling 35 machine at a small cost.

With these and other objects in view, the invention consists in the novel construction, arrangement and formation of parts, as will be hereinafter more specifically described, 45 claimed, and illustrated in the accompanying drawings, in which drawings:

Figure 1 is an end elevation of a tie handling machine showing the improved compensating plates incorporated therewith,

Figure 2 is a section taken on the line 2—2 of Figure 1 showing an inner face view of one of the compensating grab plates,

Figure 3 is an enlarged fragmentary longitudinal section through one of the

grab plates taken on the line 3—3 of Figure 55 2, and

Figure 4 is an enlarged transverse sectional view through one of the compensating grab plates taken on the line 4—4 of Figure 3.

Referring to the drawings in detail, wherein similar reference characters designate corresponding parts throughout the several views, the letter A generally indicates a tie handling machine, and B the 60 improved compensating grab plates incorporated therewith.

The tie handling machine A will not be described in detail in view of the fact that the same is constructed the same as my 70 prior patent heretobefore mentioned, but it can be seen that the machine A includes a plurality of grab arms 5 mounted for movement toward and away from each other. All of the arms on one side of the machine are 75 rigidly connected together by the novel grab plates B which will be hereinafter more fully described. It is to be noted that the outer face of the grab plate is provided with a longitudinally extending rib 6 which

is adapted to be received in suitable notches 7 formed in the inner faces of the grab arms 5. The extreme lower ends of the grab arms 5 are also provided with inwardly extending lugs 8 which are fitted within 80 notches 9 formed in the lower end of the grab plate. After the grab plate has been disposed in position on the arms the same is held against displacement by means of

U-shaped bolts 10. Each grab plate is 90 provided with a plurality of equidistantly spaced opening 11 in which are slidably mounted pistons or bolts 12 which are adapted to extend inwardly toward the longitudinal center of the machine. The 95 outer ends of the bolts are provided with stop members 13 which in the drawings are in the nature of nuts threaded on the outer ends of the bolts. The inner ends of the bolts or pistons are provided with heads 14 100 which carry the concavo-convex shaped tie engaging cups 15. The inner portion of the cups at the periphery thereof are provided with cutting edges 16 for biting into the tie terminals.

Each of the bolts or pistons 12 has coiled around it the same relatively heavy coil springs 17 the opposite ends of which en-

gage respectively the inner faces of the grab plates and the inner faces of the cups 15 and it can be seen that these springs will normally urge the cups toward the 5 longitudinal center of the machine.

In actual use of my original tie handling machine, I found that the railroad ties varied in lengths from one to three inches which made it extremely hard for the rigid 10 projection on the grab plate to engage the ties.

In the present device the grab plate will conform to the length of the tie and firmly engage the terminals thereof and prevent 15 accidental slipping movement of the ties.

Changes in details may be made without departing from the spirit or the scope of this invention, but:

What I claim as new is:

20 1. In combination a grappling mechanism including a plurality of pairs of grappling arms movable toward and away from each other, a grab plate connecting the arms of each pair of arms together, and means 25 carried by the grab plates for compensating for different lengths of ties.

2. In combination, a grappling mechanism including a plurality of pairs of grappling arms movable toward and away 30 from each other, a grab plate connecting the arms of each pair of arms together, and inwardly urged sliding members carried by each grab plate for engaging the terminals 35 of the work handled by the mechanism.

3. A grappling device including a plural-

ity of grappling arms arranged in pairs, a pair of grab plates carried by the grappling arms, and spring pressed concavo-convex-shaped cups carried by the inner 40 of the plates for engaging the work being handled.

4. In a grappling mechanism, a plurality of grappling arms arranged in pairs, a grab plate connecting the arms of each pair together, a plurality of independently movable bolts carried by each grab plate, means carried by the bolts for engaging the work handled, and means for normally urging the work engaging means toward the work.

5. A grappling mechanism including a plurality of grapple arms arranged in pairs, a pair of grab plates connected with the grapple arms, a plurality of independent sliding bolts associated with the grab plates, concavo-convex-shaped work engaging cups connected with the inner ends of the bolts, and expansion springs coiled about the bolts having their opposite ends engaging respectively the grab plate and the inner faces of the cups.

6. In a grappling mechanism, a concavo-convex-shaped work engaging cup having its inner face at the periphery thereof provided with a cutting edge.

In testimony whereof I affix my signature in presence of two witnesses,

CHARLES WESLEY LEWIS.
